RESERVE SHUTTLE CONTROL FOR
SHUTTLE CHANGING LOOMSAugustin J. Chevrette, Worcester, Mass., assignor
to Crompton & Knowles Loom Works, Worcester, Mass., a corporation of Massachusetts

Application November 27, 1943, Serial No. 511,968

13 Claims. (Cl. 139—232)

This invention relates to improvements in shuttle changing looms and it is the general object of the invention to provide improved means for supporting a reserve shuttle as it passes from the magazine to the loom lay.

In a form of shuttle changing loom which has gone into extensive use two stacks of reserve shuttles are held in a stationary magazine so located as to effect transfer of a shuttle from the magazine to the lay when the latter is in its rear position. In this type of loom the shuttles of at least one stack are released and fall by gravity upon a platform fixed to the lay when the latter is in a forward position. Rearward movement of the lay carries a transferring shuttle box on the lay to a position under the shuttle so that it can drop into the box. The bottom shuttle of the other or rear stack is always at the transferring level and is pushed forwardly by a plunger or the like along the aforesaid platform so that it will be in position to drop in the transferring box when the lay is on back center. The transferring shuttle box is part of a two-cell gang of shifting shuttle boxes on the lay under the magazine and these boxes are normally in down position. When a transfer is to occur the boxes are raised so that the oncoming empty shuttle enters the lower box and the top box is lifted to a position where it can receive a reserve shuttle from the platform when the lay reaches back center.

In looms of the aforesaid type the platform has previously been rigidly attached to the lay, or has been of such form and mounting that it cannot move downwardly when a shuttle falls on it. As a result of this construction there is some rebounding on the part of the dropping shuttle and time must be allowed for the shuttle to come to rest at the proper level for transfer. This time requirement has the effect of causing relatively slow loom speed.

It is an important object of my present invention to provide a reserve shuttle receiving platform so mounted that it can yield downwardly under the weight of the falling shuttle and act as a shock absorber to permit the shuttle to come to rest at the proper level for transfer earlier than is possible with the previously used platforms. Inasmuch as the rebounding is eliminated it is possible to operate the loom at a higher rate of speed.

It is necessary incidental to a changing operation to restore the platform to its raised position preparatory to the next transfer operation of the loom. It is accordingly another object of my present invention to provide a resetting mecha-

nism to lift the platform to its normal position. This mechanism performs its resetting operation after the platform has moved to a position behind the shuttle so that the latter will not be upset or turned or otherwise disturbed as it drops into the transfer shuttle box.

As previously stated the general type of loom to which my invention is more generally applicable has a rear stack of shuttles the lowest of which is at the transferring level. In order to make my present invention available for both stacks of shuttles I alter the construction of the previously used shuttle magazine sufficiently to permit the improved yielding platform to be common to both stacks.

With these and other objects in view which will appear as the description proceeds, my invention resides in the combination and arrangement of parts hereinafter described and set forth:

20. In the accompanying drawing, wherein a convenient embodiment of my invention is set forth,

Fig. 1 is a side elevation of a shuttle changing magazine and adjacent part of the lay together with the shuttle release mechanism and having my invention applied thereto,

Fig. 2 is a plan view looking in the direction of arrow 2, Fig. 1,

Fig. 3 is a detailed vertical section on line 3—3 of Fig. 1, on an enlarged scale, and

Fig. 4 is an operating view similar to the lower part of Fig. 1 and showing the lay and its shuttle boxes in two positions.

Referring particularly to Fig. 1, I have shown a magazine M which is mounted in fixed position with respect to the loom frame F. The magazine is provided with front and back stacks of reserve bobbins R and R', respectively, each having its own release mechanism for the bottom shuttle under control of parts not shown in the drawing but well understood. The front of the magazine is provided with a small shaft 10 to which is secured a depending supporting finger 11 normally in position to support the bobbins in the stack R. A friction arm 12 secured to shaft 10 is movable into position for engagement with the next to the bottom shuttle in the front stack at the time of a shuttle change involving the front stack, but is ordinarily out of holding position, as shown in Fig. 1. In order to effect delivery of the bottom shuttle from the front stack the shaft 10 is rocked in a clockwise direction as viewed in Fig. 1 to move the supporting finger 11 forwardly from under the bottom shuttle in stack R and at the same time move the friction arm 12 rearwardly to engage the next to the

bottom shuttle in stack R to support the superposed shuttles.

Rocking of shaft 10 is effected by means of an arm 13 secured to shaft 10 and connected to a rearwardly extending rod 14 attached to the upper end of an arm 15. The latter is secured to a shaft 16 mounted in a bearing stand 17 secured to and depending from a support 18 rigid with respect to the loom and the magazine. A second arm 19 secured to shaft 16 is connected to a depending actuator rod 20 leading to well-known control mechanism. Under normal conditions the arms 13 and 15 are in forward position and arm 19 is raised, being held in that position by a spring 21.

The rear stack R' is provided with a similar type of release and includes a second short shaft 25 similar to shaft 10 and mounted on the back of the magazine. Shaft 25 has secured thereto a depending supporting finger 26 for the bottom shuttle of the rear stack R' and a friction arm 27 similar to friction arm 12 for engagement with the next to the bottom shuttle of the rear stack during a shuttle change involving stack R'. A rearwardly extending arm 28 is secured to shaft 25 and is connected by link 29 to a lever 30 mounted for oscillation on shaft 16. The rear arm 31 of lever 30 is connected to a second depending rod 32 similar to rod 20 and connected to the aforesaid control, and a spring 33 similar to spring 21 normally holds arm 31 up. Arm 28 is normally down and arm 31 up, so that the support finger 26 will be under the bottom shuttle of rear stack R', but when delivery of a shuttle is called from the rear stack rod 32 and arm 31 are depressed to raise arm 28 and thereby rock shaft 25 in a counter-clockwise direction as viewed in Fig. 1 to move the supporting finger 26 rearwardly from under the bottom shuttle of stack R' and also move the friction arm 27 against the next to the bottom shuttle in stack R' to support the superposed shuttles.

The lay L swings back and forth in usual manner and is provided with a gang G of shuttle boxes having top and bottom cells 35 and 36, respectively. The gang G is ordinarily down so that shuttle box or cell 36 is below the race and cell 35 is even with the race to receive the shuttle approaching from the opposite end of the loom. The gang G remains in its down position between transferring operations of the loom, but when a change of shuttles is indicated the gang is raised by a force transmitted through rod 37 connected to the bottom of the gang. This upward movement of gang G occurs when the lay is in the forward part of its movement and as the lay moves rearwardly a stud 38 on cover 39 for the top cell 35 engages a cam 40 fixed to and depending from the magazine for the purpose of rocking the cover upwardly about its lay carried pivot 41 as the lay moves rearwardly. The operation of the cam and cover is indicated in Fig. 4 wherein the full lines indicate the normal position of the cover when the gang G is down and wherein the dotted lines show the effect of engagement between the stud or lug 38 and the cam 40 when gang G is up and the lay is on back center.

A back stop 45 is provided for the shuttles which drop from the magazine and is mounted on an arm 46 the upper end of which is secured as at 47 to a fixed part of the magazine. The back and forth position of the back support is determined by a stop screw 48 in arm 46 positioned to engage the magazine. The gang G includes in its construction an upwardly extending abutment or

shoulder 50 which cooperates with the back stop 45 to position a shuttle in transfer position.

In the operation of that part of the mechanism thus far described the gang G is normally down and the supporting fingers 11 and 26 are under their respective stacks R and R'. As the shuttle corresponding to the front stack R indicates weft exhaustion by a weft detector not shown the train of mechanism not shown herein but well understood is caused to rock levers 13 and 15 rearwardly by downward motion of rod 20 to effect release of the bottom shuttle of stack R while the lay is in the forward part of its motion. Similarly, if the shuttle corresponding to stack R' indicates exhaustion, the bottom shuttle of the rear stack will be released and it will fall toward transfer position.

The matter thus far described, except as noted, is of the same general construction as that previously used and shown in several patents among which may be mentioned Nos. 2,054,171, 2,082,919 and 2,103,800 to Turner. The releasing mechanism effected by downward movement of the rods 20 and 32 may be the same as that previously known, but the release of the shuttles from the rear stack R' and the sweep of the lay with respect to the magazine differ somewhat from prior looms.

The yielding platform forming an important part of my present invention is mounted on a support 55 secured at 56 to a shelf 57 on lay end 58. The support 55 extends rearwardly from the lay and has a depending wing 60 on which is mounted a stud or screw 61 passing through the hub 62 of a yielding platform designated generally at P. This platform comprises right and left hand platform rails 65 and 66, respectively, as viewed in Fig. 2, connected by a cross bar 67 which in turn is attached by arm 68 to the hub 62. As shown more particularly in Fig. 3 the stud or screw 61 passes through the wing 60 and hub 62 and supports a friction disk 70 between these last named parts which is rendered effective to resist relative movement between the hub 62 and the wing 60 by means of a compression spring 71. An adjusting nut 72 permits variation of the compression of spring 71 to alter the frictional effect which the disk exerts on the parts which it contacts.

Hub 62 has a depending arm 75 to which is attached the lower end of a light tension spring 76 the upper end of which is attached as at 77 to the support 55. The spring 76 and friction device serve normally to hold the platform rails 65 and 66 in the raised position indicated at position I, Fig. 1.

When a shuttle is dropped from the rear stack R' it falls on the raised rails 65 and 66 in front of the stop 45 and by its weight overpowers the spring 76 and the friction device, thereby lowering the platform to the position shown in Fig. 4 and position II, Fig. 1. In this position the rails are stopped from further descent by shelf 57 and the shuttle is at the proper level for a shuttle changing operation, with the forward ends of the rails behind front wall 78 of lay end 58. This downward movement of the yielding platform occurs as the lay is moving rearwardly and when it reaches back center position with cover 39 and the box cell 35 raised the latter will be under the rear stack R' and the lay will have carried the platform to its rearmost position from under the shuttle and with the forward ends of the rail 65 and 66 slightly behind the rear wall of the shuttle. The shoulder 50 is against or close to the front wall of the shuttle at this time and cooperates

with the stop 45 to position the shuttle S accurately so that it will drop into the temporarily raised box cell 35. At this same time the exhausted shuttle corresponding to the rear stack R' is approaching the temporarily raised box cell 36 and will enter the latter approximately at the following bottom center as the lay moves forwardly. The gang G thereupon descends to carry the newly transferred shuttle from stack R' and in box cell 35 down to picking position, and at the following top center the shuttle is picked across the loom. Meantime the depleted shuttle in the bottom cell 36 is discharged forwardly in well-known manner not indicated herein.

Transfer of a shuttle from the front stack R is similar to that already described with respect to the rear stack, the bottom shuttle of the front stack falling on the front parts of the platform rails 65 and 66 to cause the latter to descend. As the lay recedes the rails 65 and 66 move the shuttle rearwardly against stop 45 and the latter cooperates with shoulder 50, as previously described, to position the shuttle for dropping into box 35 when the lay reaches the rear position indicated in dotted lines in Fig. 4. Transfer of the shuttle derived from the front stack R is thus similar to that described previously in connection with the shuttle derived from stack R'.

It will be noted from Fig. 1 that the platform rails 65 and 66 are normally above the center support 55 and above the normal transfer position for the shuttles. As the latter are released they fall on and by their weight cause downward movement of the rails until the latter rest on shelf 57, at which time the shuttle is at proper level for transfer. The rails descend against the action of spring 76 and the friction device, and act as a shock absorber for the shuttle, permitting the latter to reach correct position without rebounding. The weight of the shuttle and the effect of the friction device are such as to hold the rails down against the action of spring 76 during the transferring operation.

The friction device may under some settings thereof prevent the spring 76 from returning the rails to their normal raised position after the weight of the shuttle is removed, and for this reason I prefer to use some means for resetting the platform. To effect this result I use a stop 80 shown in Fig. 1 comprising a preferably resilient arm the upper end of which is secured to the stand 18 and the lower end of which may have a stop pad 81 for engagement with the depending arm 75 of the platform P. It will be understood that when the platform is down it will be in the dotted line position indicated in Fig. 1 and arm 75 will be to the rear of its normal position relatively to the lay. As the lay completes its rearward movement on a transferring beat the pad 81 will strike arm 75 and move the latter in a clockwise direction around the stud or screw 61, thereby lifting the platform and restoring the rails 65 and 66 to their normal up position where they are held by the spring 76 and friction device.

It is necessary to delay the resetting operation until there is no danger that the up movement of the platform rails will disturb the shuttle in transfer position. This delay is assured by making the rails 65 and 66 short enough so that their forward ends will be located behind the front wall 78 of lay end 58 by a distance greater than the distance through which pad 81 moves that part of arm 75 which it engages. During rearward movement of the lay, therefore, the back

wall of the shuttle will have passed to a position in front of the rails before the pad 81 engages arm 75, and when this last named engagement occurs the rails will start to move upwardly behind and out of engagement with the shuttle in transfer.

From the foregoing it will be seen that I have provided a simple form of shock absorbing platform to support a shuttle passing from the magazine to the lay so constructed and mounted that it lowers the shuttle gently. As a result of the downward movement of the rails 65 and 66 the shuttle in transfer comes quickly and easily to transfer position with no unnecessary or time consuming vibration or rebounding. It will also be seen that the platform is reset at a time in the cycle of the transferring operations after the shuttle in transfer has moved to such position that the rising rails 65 and 66 will not disturb it. It will furthermore be seen that the yielding platform is common to both stacks R and R' and that the resetting incident to one shuttle changing operation occurs before a second shuttle changing operation can occur. While I have shown the magazine in such position that its rear stack will be over box cell 35 when the lay is in rear position I do not wish necessarily to be limited to this construction. It is also apparent that my invention is not necessarily limited to those types of shuttle changing looms involving multiple stacks of reserve shuttles. Furthermore, the friction device shown in Fig. 3 can be omitted but its use tends to prevent vibration of the platform relatively to the lay.

Having thus described my invention it will be seen that changes and modifications may be made therein by those skilled in the art without departing from the spirit and scope of the invention and I do not wish to be limited to the details herein disclosed, but what I claim is:

1. In a shuttle changing loom having a stack of reserve shuttles which are delivered downwardly one by one preparatory to shuttle changing operations, a lay reciprocating horizontally under said stack, a shuttle box on the lay below the stack to receive a shuttle from the stack during a shuttle changing operation, and shock absorbing mechanism mounted on the lay for vertical movement relatively thereto and movable back and forth therewith and resisting downward movement of a shuttle delivered from the stack but overpowered by the shuttle and serving to position the shuttle for a shuttle changing operation with respect to said shuttle box.

2. In a shuttle changing loom having a stack of reserve shuttles which are delivered downwardly from the stack one by one incident to shuttle changing operations, a lay under the stack, a shuttle box on the lay, a normally raised shock absorbing platform under the stack, in the path of a shuttle descending from the stack, and stop means on the lay to engage the platform when the latter is in low position, a shuttle dropping from said stack falling on the platform and moving the latter downwardly against said stop means and said platform thereby effecting placement of the shuttle at the proper level for a shuttle changing operation with respect to said shuttle box.

3. In a shuttle changing loom having a stack of reserve bobbins and release mechanism by which the shuttles are dropped from the bottom of the stack preparatory to transfer, a reciprocating lay having a shuttle box thereon to receive

a shuttle being transferred, a shuttle receiving platform movably mounted on and reciprocating with the lay under the stack, and yielding means normally holding the platform in raised position, a shuttle when released from the stack falling on the platform and lowering the latter to a level for proper delivery of the shuttle into said shuttle box.

4. In a shuttle changing loom having a stack of reserve shuttles which are delivered downwardly from the stack during shuttle changing operations, a lay reciprocating back and forth under said stack, a shuttle box on the lay below said stack to receive a shuttle during a shuttle changing operation, a platform pivoted on the lay and extending rearwardly from said shuttle box and located under said stack, and yielding means holding said platform normally in raised position but yieldable downwardly under the weight of a shuttle delivered from said stack to place the shuttle in position for movement into said shuttle box.

5. In a shuttle changing loom having a stack of reserve shuttles which are delivered downwardly from the stack during shuttle changing operations, a lay reciprocating back and forth under said stack, a shuttle box on the lay below said stack to receive a shuttle during a shuttle changing operation, platform rails under said stack, means pivotally connecting said rails to the lay for vertical movement relatively thereto, and yielding means resisting downward movement of the rails with respect to the lay and normally holding said rails in raised position with respect to the lay, a shuttle when released from the stack moving downwardly on said rails and overpowering said yielding means to cause the latter to move downwardly with respect to the lay and effect positioning of the shuttle for a shuttle changing operation with respect to the lay.

6. In a shuttle changing loom having a stack of reserve shuttles which are delivered downwardly from the stack one by one during shuttle changing operations, a lay reciprocating back and forth under said stack, a shuttle box on the lay below said stack to receive a shuttle during a shuttle changing operation, a vertically movable platform under the stack, resilient means normally holding the platform in raised position with respect to the lay, and means to cause the platform to move backwardly and forwardly with the lay, a shuttle when released from said stack falling on the platform and overpowering said resilient means and moving said platform downwardly against the action of said resilient means to place the shuttle in position for a shuttle changing operation.

7. In a shuttle changing loom having a stack of reserve shuttles which are delivered downwardly from the stack one by one during shuttle changing operations, a lay reciprocating back and forth under said stack, a shuttle box on the lay below said stack to receive a shuttle during a shuttle changing operation, a vertically movable platform under the stack, friction means normally holding the platform in raised position with respect to the lay, and means to cause the platform to move backwardly and forwardly with the lay, a shuttle when released from said stack falling on the platform and overpowering said friction means and moving said platform downwardly against the action of said friction means to place the shuttle in position for a shuttle changing operation.

8. In a shuttle changing loom having a stack of reserve bobbins which are released for downward movement therefrom one by one preparatory to shuttle changing operations, a lay reciprocating back and forth under the stack, a shuttle box on the lay below the stack to receive a shuttle derived from the stack during a shuttle changing operation, a shock absorber mechanism mounted on the lay for vertical movement relatively thereto and normally in raised position for engagement with a shuttle released from said stack and moved downwardly by the shuttle to position the latter for a shuttle changing operation, and means operative due to movement of the lay to reset said shock absorber mechanism to the normal raised position thereof.

9. In a shuttle changing loom having a stack of reserve bobbins which are released for downward movement therefrom one by one preparatory to shuttle changing operations, a lay reciprocating back and forth under the stack, a shuttle box on the lay below the stack to receive a shuttle derived from the stack during a shuttle changing operation, a shock absorber mechanism pivotally mounted on the lay for vertical movement relatively thereto and normally in raised position for engagement with a shuttle released from said stack and moved downwardly by the shuttle to position the latter for a shuttle changing operation, and a substantially stationary member engaging the shock absorbing mechanism as the lay approaches the rearward position thereof to move said shock absorbing mechanism back to the normal position thereof.

10. In a shuttle changing loom having a stack of reserve bobbins which are released for downward movement therefrom one by one preparatory to shuttle changing operations, a lay reciprocating back and forth under the stack, a shuttle box on the lay below the stack to receive a shuttle derived from the stack during a shuttle changing operation, a shock absorber mechanism mounted on the lay normally in raised position for engagement with a shuttle released from said stack and moved downwardly by the shuttle to position the latter for a shuttle changing operation, a stop limiting rearward movement of a shuttle on the platform and causing the latter to move under the shuttle as the lay moves rearwardly and cause the shuttle to assume a position in front of said platform at a given point in the rearward movement of the lay during a shuttle changing operation, and means operative during the rearward movement of the lay subsequent to said point to return the platform to the normal position thereof.

11. In a shuttle changing loom having a pair of stacks of reserve bobbins and means to release shuttles from each stack for downward movement incident to shuttle changing operations, a lay reciprocating back and forth under said stacks, a shuttle box on said lay movable by the latter to register with the rear stack when the lay is in the rearmost position thereof, and a shock absorbing shuttle receiving platform mounted on the lay for downward movement relatively thereto and normally in raised position to receive a shuttle released by either stack and move downwardly with the shuttle due to the weight of the latter to effect placement of the shuttle at the proper level for entry into the shuttle box incident to a shuttle changing operation.

12. In a shuttle changing loom having a pair of stacks of reserve bobbins and means to release shuttles from each stack for downward

movement incident to shuttle changing operations, a lay reciprocating backwardly and forwardly under said stacks, a shuttle box on said lay movable by the latter to register with the rear stack when the lay is in the rearmost position thereof, an abutment on the lay, a stop adjacent to the bottom of the rear stack, a shock absorbing platform extending under both stacks and normally in raised position to receive a shuttle derived from either stack, said abutment during the rearward movement of the lay cooperating with said stop to position a shuttle derived from either stack in proper position for downward movement into the shuttle box when the lay reaches the rearmost position thereof, said platform moving downwardly with the shuttle due to the weight of the latter to place the shuttle at the proper level for a shuttle changing operation with respect to the shuttle box.

13. In a shuttle changing loom having a pair of stacks of reserve bobbins and means to release shuttles from each stack for downward movement incident to shuttle changing operations, a lay reciprocating backwardly and forwardly under said stacks, a shuttle box on said lay movable by the latter to register with one of said stacks when the lay is in the rearmost position thereof, a shock absorbing platform common to and located under said stacks and normally in raised position and placed for engagement by a shuttle derived from either stack, a shuttle when falling from either stack engaging the platform and moving the latter downwardly, and stop means on the lay limiting downward movement of the platform and causing the latter to place a shuttle at the proper level for a transferring operation with respect to said shuttle box.

AUGUSTIN J. CHEVRETTE.
